UNITED STATES PATENT OFFICE.

HERBERT A. FLACK, OF CHEROKEE, IOWA.

FOLDING BOX.

1,112,442.

Specification of Letters Patent.

Patented Oct. 6, 1914.

Application filed July 21, 1913. Serial No. 780,199.

To all whom it may concern:

Be it known that I, HERBERT A. FLACK, a citizen of the United States of America, and a resident of Cherokee, Cherokee county, Iowa, have invented certain new and useful Improvements in Folding Boxes, of which the following is a specification.

My invention relates to folding boxes, and the objects of my improvements are these: 10 First, to form a box of a connective plurality of parts preferably stamped out in the first instance in one piece from suitable material or of corresponding parts susceptible of being connected together with the 15 use of other fastening-means, and the peculiar foldings and engagements of certain of the parts upon and with each other; second, the securing together and reinforcing of the angles and corners of the box in such 20 a manner as to not only greatly strengthen the structure, but also prevent displacement of parts of the box while in use; third, to cause certain parts of the structure to bear against other parts thereof when brought 25 together into mutual engagement at or adjacent to the angles of the box, so that one of said fastening-means is reinforced and secured by means of the other fastening-means; fourth, to provide a folding structure, which, when brought together shortly, 30 resist not only collapsing forces exercised from the outside thereof, but will also have its parts held more securely together by means of the contents of the box bearing 35 against certain parts thereof; fifth, to arrange such a folding cover adapted to enwrap the top and certain of the angles of the box such as will more completely protect the contents of the box when filled; 40 sixth, to arrange the folding flaps and parts of the box in such a manner as to permit of a plurality of compartments being established in the box, in which articles may be segregated from each other. These objects 45 I have accomplished by the means which are hereinafter described and claimed, and which are illustrated in the accompanying drawings, in which:

Figure 1 is a plan view of a piece of material which is cut and scored to produce a blank embodying some of the features of my invention. Fig. 2 is a perspective view illustrating the blank of Fig. 1 in a partly folded position to produce the box in the first stage 55 of assembling the folded parts together. Fig. 3 is a plan view of the blank in a fur-

ther stage of its folding, showing it in its completely folded condition, except for the enwrapping of the cover flaps thereover. Fig. 4 is a perspective view of the box in its 60 completely folded condition. Fig. 5 is a broken detail perspective view of the part of the folded blank, showing the coöperating angle securing-means. Fig. 6 is a plan view of a piece of material which is cut and 65 scored to produce a blank embodying slightly varied and additional features of my invention. Fig. 7 is a plan view of the blank of Fig. 6, in a partially folded condition, in which the end walls only of the low- 70 ermost compartment are connected together. Fig. 8 is an enlarged perspective view of the blank of Fig. 6, showing it in a secondary stage of folding. Fig. 9 is a plan view similar to Fig. 7, but showing a still more advanced stage of the folding, in which the lowermost compartment has been completely 75 formed and the uppermost compartment parts established before the cover flaps have been folded thereover.

Similar numerals of reference and characters of reference denote corresponding parts throughout the several views.

Referring first to Figs. 1 to 5, inclusive, which show the primary and simplest form 85 of my invention, Fig. 1 illustrates a blank formed of a piece of paper-stock or other suitable material, which is cut and scored suitably, preliminary to being folded into box form. Said blank has cuts or incisions, 90 a' and b' . It also has scorings or creases c' , c^2 , d' , e' , f' , i' , i^2 , i^3 , k' , k^2 , k^3 , g and h . The blank consists of the bottom 1, the side-folds 2 and 3, and the end-folds 18 and 19. The end-fold 19 has a cover-fold 95 20, which latter has an end-flap 21. The side-fold 2 has on opposite ends the end-flaps 4 and 5, which are respectively furnished with the tabs 8 and 9. The other side-fold 3 has on its opposite ends, likewise, the flaps 6 and 7, which are respectively furnished with the end-tabs 12 and 13. The side-flap 2 also has a top-flap 10, having on its opposite ends the tabs 14 and 15, respectively. The other side-fold 3 has 100 a like top-flap 11, whose opposite ends are supplied with the tabs 16 and 17, respectively. It will be seen that the bottom 1 is in one continuous piece with the end-folds 18 and with the cover-flap, composed of the parts 19, 20 and 21. The oppositely located side-folds 2 and 3, with their respective tabs 105 110

4, 5 and 10, and 6, 7 and 11, are of the same form and dimensions. It is to be understood, however, that in the employment of my invention, I do not restrict myself to any particular material, form or dimension of the box or of the respective parts thereof, any more than to use such as would properly come within the scope of the invention, and that instead of the creases or scorings between the parts, the parts may be separately formed and afterward connected together by any suitable means to provide flexible joints at their respective proper places to form a receptacle such as is contemplated in this invention.

The tabs 14, 16 and 17 are shown as having one angle of each removed to form a tongue-shaped piece in each case for convenience, although they may all be formed similar to the tab 15, which is oblong in shape. The other tabs, 8, 9, 12 and 13 are made in a narrowed form projected from the middle of the end of the flaps 4, 5, 6 and 7, for the purpose of being fittingly received within the slots l , l' , m and m' , formed respectively in the middle of the creases i^2 , i^3 , k^2 and k^3 .

Referring to Figs. 2 and 3, which represent different stages of the process of folding the parts of the blank into a box, Fig. 2 shows the side-folds 2 and 3, bent upward at angles to the bottom 1, along the creases c , with the flaps 4 and 7 bent on the creases i^2 and k^3 inwardly to have their end tabs 8 and 13 lie along the abutting inner walls of the said folds 2 and 3, respectively. The other flaps 5 and 6 are then brought over to lie upon the outside of the said flaps 7 and 4, respectively, with their end-tabs 9 and 12 respectively passed through the slots m' and l , to lie along the inner walls of said folds 2 and 3.

Referring now to Figs. 3 and 5, the top flaps 10 and 11 are next bent over horizontally on the creases d and d' , respectively. The end-tabs 14 and 15, and 16 and 17, being first bent up on the creases e , e' , and f , f' , and said tabs then being pushed downwardly when the top folds 11 are bent over horizontally to lie in juxtaposition to the abutting flaps 7 and 4, respectively, with the edges of said tabs which lie along the incisions b and b' contacting with the tabs 8, 9, 12 and 13, which lie between them and the said side-folds 2 and 3, the partially folded box is then in a position presenting the form shown in Fig. 3, and when the end-flap 18, and the combined end and cover-flaps 19, 20 and 21 are carried up over the ends 5 and 6, and with the part 20 lying horizontally upon the top-folds 10 and 11, the box is in its closed condition shown in Fig. 4. Any suitable fastening-means may then be employed to secure said cover parts 19, 20 and 21 upon the other parts of the box. Special

attention is invited to Fig. 5, which illustrates the angle connections and reinforcements of the box. It will be seen that the end-parts 5 and 7 form a double wall, while the side-fold 3 and the overlying tab 9 form a structure of double thickness at the angle of the box, while the in-turned tab 17 supplements each of these reinforced parts, at the same time, locking the tab 9 against the inner wall of the part 3. It is obvious that when the box is closed and covered that any exteriorly applied force will meet with a maximum of resistance at these angles, while at the same time forcing the interlocked parts into more intimate connection. When the box is filled, the contents will bear against the parts described at the angles, and tend to hold them in close contact preventing displacement thereof. The top-folds 10 and 11 offer added reinforcements to the longitudinal upper angles of the box and to the upper corners against any operating force, while acting as trusses to the side walls 2 and 3. The cover part 20, with the end-parts 18, 19 and 21 reinforce the ends and top of the box, and taken together, make a very rigid structure from the lightest material.

The folding-box illustrated in Figs. 1 to 4, inclusive, is the simplest basic form of my invention, but I have shown in Figs. 6 to 9, inclusive, a folding box, which comprises the same principles of construction and arrangement, with some added parts, adapted to coöperate with the other parts to supply two compartments therein, adapted to receive and hold separated contents. The blank shown in Fig. 6 has the incisions y , y' , z , z' , z^2 , z^3 . It also has the scorings or creases j , j' , n , n' , s , s' , t , t' , u , u' , w , w' , x , x' , o , p , q and r . The part 22 forms the bottom of the box, and lies in alinement with the oppositely directed folding parts 46, 47 and 48, extending from the left-hand crease j' and the parts 49, 50 and 51 extending from the right-hand crease j . At right angles to the strip composed of said parts are the side-folds or parts 23 and 25, extending from the upper crease j , and the parts 24 and 26 extending from the lower crease j . The side-fold 23 has on its opposite ends the pairs of flaps 31 and 35, and 33 and 37, respectively, said flaps having respectively at their ends the tabs 32, 36, 34 and 38. The top-flap 25 of the part 23 has on opposite ends the truncated tabs 27 and 28, respectively, and the other top-flap 26 on the part 24 has like truncated oppositely-disposed tabs 29 and 30. The side-fold 24 also has like oppositely-disposed pairs of similar flaps 42 and 39, and 44 and 58, which have their tabs 43, 40, and 45 and 41, respectively. I have provided middle slots 52, 53, 54, 55, 56 and 57 along or adjacent to the creases u , x , t , t' , w and w' , adapted to receive certain of the

end-tabs previously described during the process of folding the parts of the box together.

Referring now to Figs. 7 to 9, inclusive, illustrating three different stages of the folding process, the Fig. 7 shows a stage of the folding of similar parts, which is like that illustrated in Fig. 2 of the simpler form of the box, and the analogous parts are connected up in the same way and with the same results, and this stage will not be further described. In Fig. 8, the folding parts 46, 47 and 48 are shown as carried partially over the lowermost compartment formed as above described and illustrated, to overhang same, and the process of finishing the lowermost compartment is completed by merely carrying said parts over until the middle fold 47 forms a cover for said lowermost compartment, with the folds 46 and 48 respectively covering the end-pieces 39 and 33, respectively.

In order to form a second or superposed compartment, the upper end-flaps 35 and 42, and 37 and 44 are folded inwardly to overlie each other respectively in pairs in a similar way to the method for arranging the other end-flaps 31 and 39, and 33 and 58 lying thereunder. The tabs 38 and 43 are pushed through the slots 56 and 52, respectively, and then the top-flaps 25 and 26 are folded over toward each other horizontally with their end-tabs 27 and 28 and 29 and 30, bent over at right angles and pushed down into the box to engage the end-tabs 36, 38, 43 and 45, and lock the same in place in a similar way to that shown in Fig. 5. The end-fold 49 is then bent up on the crease j' to overlie the abutting end of the two compartments and the top part 50 brought over to close the top of the uppermost compartment, with the end part 51 brought down upon the opposite end-wall of the box. Any suitable means may then be used to secure the cover upon the box, as previously mentioned. It will be seen that the last device shown and described is simply the same as the first described device, with the mere addition of the compartment producing means. The angles of the box thus formed are reinforced and secured in the same way, and the box is throughout formed and strengthened in the same manner as that shown in Figs. 1 to 5, inclusive.

It will be obvious that each of the angles and corners of my box are so overlaid with other parts when folded together that the contents are prevented from leaking out. It is also obvious that the two compartment boxes described may be variously modified and other compartments added and connected together in a like manner, without departing from the principle of my invention.

Having described my invention, what I claim as new, and desire to secure by Letters Patent, is:

1. A folding box, comprising a bottom having side folds on two opposite sides, the said folds having end-flaps provided with end-tabs, and each of said end-flaps having a transverse slot extending along its line of junction with the carrying side-fold, the end-flaps folded over each other to form box-sides, entire throughout and of double thickness, when the end-tabs on the outer flaps are inserted in the slots in the inner flaps so as to lie along the inner walls of the adjacent side folds.

2. A folding box, comprising a bottom having side folds on two opposite sides, the said folds having end-flaps provided with end-tabs, each of said end-flaps having a transverse slot extending along its line of junction with the carrying side-fold, the ends flaps adapted, when folded over each other, to form box-sides of double strength, when the end-tabs on the outer of said end flaps are inserted in the slots in the inner end flaps so as to lie along the inner walls of the adjacent side folds; with the end tabs on the said inner flaps lying along the inner walls of the adjacent side folds.

3. A folding box, comprising a bottom having side folds on two opposite sides provided with top flaps having end-tabs, the first-mentioned folds having end-flaps provided with end-tabs, each of said end-flaps having a transverse slot extending along its line of junction with the carrying side-fold, the end-flaps folded over each other to form box-sides when the end-tabs on the outer flaps are inserted in the slots in the inner flaps to lie along the inner walls of the adjacent side-folds, and the side-fold top-flaps folded over the box opposite its bottom, with their end-tabs folded inwardly to engage the first-mentioned infolded end-tabs.

4. A folding box comprising a bottom, two side folds, end flaps on each side fold, a top flap on each side fold, end tabs on each end flap and on each top flap, end folds on said bottom, a top fold on one of the last mentioned end folds, and an end flap on the said top fold, certain of the side fold end flap tabs having locking engagement with the side fold opposite thereto, and the top flap end tabs bearing against said end flap tabs to hold them against the abutting side folds with which they are engaged.

5. A folding box comprising a bottom, side and end folds, top folds on the end folds, a pair of end flaps on each end of each side fold, each side fold end flap having locking engagement with the opposite side fold, one end with its top fold dividing the interior of the box into two compart-

ments, and the other end fold with its top fold serving to cover the uppermost compartment.

6. A folding box comprising a bottom, 5 side and end folds, top folds on the end folds, a pair of end flaps on each end of each side fold, each side fold end flap having locking engagement with the opposite side fold, top flaps on said side flaps and 10 end tabs on said top flaps, one end fold with its top fold dividing the interior of the box into two compartments, the said top flaps having their end tabs foldable inwardly to engage the side fold end flap tabs between 15 them and the adjacent side folds above said dividing part, and the other end fold with its top fold serving to cover the uppermost compartment.

7. A folding box comprising a bottom, 20 side and end folds, top folds on the end folds, end flaps on said top folds, a pair of end flaps on each end of each side fold, end tabs on each end flap, said side folds and end flaps having slits at their bending 25 creases, and certain of the end tabs being adapted to enter certain of said slits to form locking engagements with said side folds, one of the end folds with its top fold serving as a partition cover over said in-

terlocked parts to provide two compartments, and the other end fold with its top flap serving as a cover for the upper compartment of the box by being passed about the uppermost interlocked side fold end flaps. 30

8. A folding box comprising a bottom, side and end folds, top folds on the end folds, end flaps on the top folds, a pair of end flaps on each end of each side fold, end tabs on each end flap, said side folds and 40 said end flap-tabs having locking engagements, with the tabs overlying the inner walls of the side folds, one of said end folds with its top fold folding over between the pairs of said side folds to serve as a partition for the box, and top flaps on said side folds having end tabs, foldable inwardly with the end tabs engaging the tabs on the side fold end flaps between themselves and the inner walls of said side folds, the other 45 end fold and its top fold serving as an outer cover for the box. 50
